UNITED STATES PATENT OFFICE.

FLOYD PAUL ARCHER, OF WILKES-BARRE, PENNSYLVANIA.

AERIAL RAILWAY.

Application filed February 11, 1926. Serial No. 87,666.

My present invention relates generally to railways, and more particularly to aerial railways, and my particular object is the provision of a monorail vehicle so constructed as to facilitate its use in the various respects to be hereinafter particularly pointed out and especially to facilitate its employment in connection with short runs.

My invention proposes a vehicle of this type which may be easily and quickly loaded and unloaded, which may be readily and easily turned in order to reverse its direction of movement without the necessity of turn tables and other complications in connection with the vehicle support, and a further and important object of the invention is to provide a vehicle of this nature having in connection therewith means adapted to contribute to its support, aside from the rail upon which it runs.

A still further object is the provision of a monorail vehicle having simple effective means to avoid excessive side sway especially when rounding curves and the like. With these general objects, further and more specific objects of the invention as well as resulting advantages thereof will become plain from a careful consideration of the following description, especially with reference to the accompanying drawings which form a part of this specification, and in which:

Figure 1 is a perspective view illustrating the practical application of my invention, Figure 2 is a top plan view of my improved vehicle in use,

Figure 3 is a vertical longitudinal section taken therethrough,

Figure 4 is a vertical transverse section taken substantially on the line 4-4 of Figure 3,

Figure 5 is a fragmentary perspective view showing in detail one of the end guide wheels and its supporting structure,

Figure 6 is a fragmentary side view showing in detail the central guide wheel and its supporting connections, and

Figure 7 is still another fragmentary side view showing in detail the brake and its operating connections.

Referring now to these figures, my invention proposes a monorail vehicle whose body or shell 10 is preferably of the cylindrical shape shown, tapering to approximately pointed fore and rear ends through the lat-

ter of which the shaft of a driving propeller 11 projects. This propeller is driven by an internal combustion motor 12 within a rear motor compartment 13, the latter of which may be and preferably is separated from the main or carrying chamber 14 of the vehicle. A lower portion of the vehicle as indicated at 15 is preferably detached from the remainder together with a corresponding portion of the inner platform or floor 16 where the vehicle is used for the transportation of passengers, and this portion which may be raised and lowered with respect to the body of the vehicle is supported upon a flexible supporting connection 17 extending over guide pulleys 18 within the body and to a drum or winch 19, the latter preferably within the motor compartment 13 and actuated by the motor 12 when the loading and unloading portion 15 of the vehicle is to be raised and lowered.

In this way a sufficient portion of the vehicle may be raised and lowered under control of mechanism within the vehicle itself to permit of rapidly loading and unloading the vehicle whether it is utilized for the transportation of passengers or commodities.

The vehicle thus adapted to proceed under its own power and to be rapidly loaded and unloaded under control of that power, is supported in use from an overhead rail 20 by means of double flanged guide wheels travelling on the rail, there being a central wheel 21 and end wheels 22, each of the latter of which as best seen in Figure 5 is mounted in connection with a supporting and journal bracket 23 having an offset lower portion 24 terminating in an angular extension 25. This extension 25 is apertured for the reception of a locking pin 26 vertically shiftable in an angular bracket 27 secured to and upstanding from the body of the vehicle 10, and this locking pin 26 is shiftable under actuation of its controlling spring 28 not only through the aperture of the extension 25, but also through the upper portion of the bracket 26. Moreover, the locking pin 26 has a depending flexible connection 29 normally within the vehicle body by means of which it may be lowered and withdrawn from the extension 25 of the wheel bracket 23 so that the ends of the vehicle body may be freed in this way from the supporting wheels 22.

The central supporting wheel 21 is on the other hand mounted in a supporting and journal bracket 30 at the upper end of an upright 31 journaled vertically through the center of the vehicle 10 and preferably provided with pivoted diametrically opposed handles 32 within the vehicle, and with an annular enlargement 33 in a swivel or journal box 34 against a portion of which the enlargement 33 has a ball or roller bearing 35.

In this way the vehicle may be reversed endwise upon the central upright 31 in connection with the central supporting wheel 21 by first releasing its connections with the end supporting wheels 22. The operator by then bracing himself within the vehicle and grasping the handles 32, may gradually swing the vehicle around upon the central upright 31 until it is turned to proceed in the opposite direction whereupon by again completing the connections with the end wheel brackets, the vehicle is ready to proceed.

25 The several supporting wheels 21 and 22 are preferably covered by a narrow elongated hood 36, and in order to assist in the support of the vehicle as a whole and relieve in part, its weight from the supporting rail 30 while the vehicle is in movement, this shield 36 which covers and protects the supporting wheels 21 and 22 is also provided at its forward and rear portions with laterally and horizontally outstanding aerofoils 37, 35 rigid with the hood and either with or without bracing of any suitable type, such as may in practice be found necessary.

Monorail vehicles are subject to certain disadvantages in use, among which may be included their susceptibility of side sway, especially in rounding curves, and in order to avoid this excessive undesirable side sway, I propose that the body 10 of the vehicle be provided at diametrically opposite points centrally of its sides with horizontally outstanding brackets 38 in which are journaled horizontal rollers 39, these rollers adapted to contact with side guide rails 40 disposed at such points in the travel of the vehicle as may in practice be found necessary and especially at curves.

It is obvious from the foregoing that in various respects, as for instance the shape of its body, the vehicle of my invention is susceptible of considerable variation and change from the particular characteristics above described, and shown in the accompanying drawings, and it is plain that being driven under its own power by means contained within the body, it is susceptible of ready support especially in view of the provision of the vehicle with means to assist in the support without complicating the

same and without adding in any material respect to its cost.

It is further obvious that the vehicle as proposed by my invention lends itself readily to ready manufacture and easy simple installation and that it is furthermore adaptable to the carrying of passengers as well as freight.

In addition to the foregoing, I may provide for checking the movement of the vehicle and may for this purpose utilize a structure as best shown in Figures 3 and 7, including an upper brake lever 41 pivoted upon a bracket 42 on the vehicle body 10 and having in connection therewith a brake shoe 43 shiftable vertically into and out of engagement with the supporting rail 20. 80 This lever 41 is secured at one end to a controlling cable or other connection 44 depending into the body of the vehicle 10 and secured at its lower end to one end of a bell crank 45, the other portion of which bell crank serves as a control lever as indicated at 46, and may be provided with a latch mechanism 47 in engagement with a notched quadrant 48.

I claim:

1. An aerial vehicle of the monorail type having supporting wheels in line thereabove and connected to said vehicle at lengthwise spaced points thereof, and means whereby the vehicle may be endwise reversed with respect to said supporting wheels.

2. An aerial vehicle of the type described, having supporting wheels in line thereabove including a central wheel and end wheels, a support connecting the vehicle with the central wheel and with respect to which the vehicle is rotatable, and detachable connections between the vehicle and the end wheels permitting endwise reversal of the vehicle with respect to the central wheel.

3. An aerial vehicle, overhead supporting wheels from which said vehicle is suspended, a hood extending over the wheels, aerofoils outstanding from the hood and means to reverse the vehicle independent of said hood.

4. A suspended aerial vehicle having upper supporting wheels in a line to engage a supporting rail, and having laterally outstanding horizontally disposed guide rollers intermediate its ends adapted to engage guide rails in use and to prevent side sway of the vehicle on its supporting rail.

5. An aerial vehicle, an overhead wheeled support for engaging a supporting rail and from which said vehicle is suspended, a swiveled connection centrally of the vehicle with said support, and detachable connections between the ends of the vehicle and said support.

FLOYD PAUL ARCHER.
